UNITED STATES PATENT OFFICE.

LOUIS HART KRICKEL, OF MONROE, LOUISIANA.

DEMOUNTABLE RIM.

1,363,604.

Specification of Letters Patent. Patented Dec. 28, 1920.

Application filed November 26, 1919. Serial No. 340,886.

To all whom it may concern:

Be it known that I, LOUIS H. KRICKEL, a citizen of the United States, and a resident of Monroe, in the parish of Ouachita and State of Louisiana, have invented certain new and useful Improvements in Demountable Rims, of which the following is a specification.

My invention relates to demountable rims. 10 An important object of my invention is to provide a demountable rim which is positively supported and secured with its parts locked in assembled position, upon the wheel, but which may be readily removed from the 15 wheel and readily and easily demounted.

Another object is to provide a demountable rim of great strength and durability, ready and reliable in operation, and easy and inexpensive to manufacture.

20 Other objects and advantages reside in the certain novel features of the construction, arrangement and combination of parts, which will become apparent as the description proceeds, reference being had to the accompanying drawings forming a part of this specification, and in which:

Figure 1 is a side elevational view of my improved demountable rim assembled and in position on the wheel felly, 30 Fig. 2 is a sectional view through the line 2-2 of Fig. 1, looking in the direction of the arrows,

Fig. 3 is an enlarged fragmentary detail view in side elevation showing the co-operation of the lock lug and impact lug,

Fig. 4 is a sectional view on the line 4-4 of Fig. 1,

Fig. 5 is a sectional view on the line 5-5 of Fig. 3,

40 Fig. 6 is a detail perspective view of the locking plate,

Fig. 7 is a detail perspective view of the locking pin.

Referring to the drawings, it will be seen 45 that the letter A designates the felly associated in the usual manner with the wheel structure (not shown). The felly band B is mounted upon the felly and is provided with an integral outwardly and upwardly extending flange C. A demountable rim indicated generally at D is mounted upon the felly band and secured in spaced relation thereto in the usual manner by the conventional lock lugs E, and their bolts F, usually 50 six in number, and the tire casing G is mounted in the rim channel in the usual

manner. In this construction conventional so far as described, the rim is supported on its inner circumferential portion by the flange C of the felly band and on its outer circumference by the lock lugs F, being spaced from the felly band. In practice, it has been found that the supporting effect of the lock lugs is inadequate, to cope with the severe strains and not only are the lock lugs 55 and their bolts bent, and in some instances, snapped off, but the rim has been distorted due to the excessive span both circumferential and lateral. One of the important features of the present invention resides in the provision of means to overcome this difficulty and bending or snapping off of the lock lugs and their bolts as well as distortion of the rim is thereby effectually prevented.

The demountable rim D comprises outer 75 and inner circumferential sections indicated at 10 and 11, respectively, the outer section being provided with an elongated cut-away portion 10' and the inner section being provided with a semi-circular cut-away portion 80 11', to accommodate the valve stem of the tire (not shown) both in the assembled position of the sections and during the relative movement of the sections in their operation from release to locked position and vice 85 versa, as will be hereinafter fully described.

The outer section 10 has secured thereto a plurality of locking pins 12 projecting radially inward from the under side of the rim section and spaced equally about the circumferential extent of the rim section. Each of the locking pins include a shank 12' seated in the outer section 10 and secured therein preferably by having the outer end of its shank burried over as seen in Fig. 4.

95 The inner section 11 has secured to its under side a plurality of locking plates indicated generally at 13, adapted to co-operate with the locking pins 12 of the outer section to lock the sections together in assembled 100 position. Each of the locking plates 13 comprises an inner portion 14 adapted to be riveted or otherwise secured to the inner section 11 and an outer portion 15 provided with a slot 16, the walls of which engage 105 with the locking pin 12 after the pin has been entered into the slot. The walls of the slot are all vertical but the outer wall 16' veers outwardly to provide an inclined plane or cam action on the locking pin to draw the 110 sections 10 and 11 together. The inner riveted portion 14 is tapered or of gradually

increasing cross section from its inner toward its outer end. This taper or increase of cross section continues from the inner end to approximately the middle of the locking plate from which point to the outer end thereof, the locking plate is of uniform and relatively thick cross section. As shown, especially in Fig. 4, the uniform cross sectioned and relatively thick portion of the locking plate is disposed to underlie the outer section 10 which section constitutes the outer portion of the rim. The tapered portion of the locking plate is disposed as shown in Fig. 4 to underlie the inner section 11 of the rim. The locking plates and pins are preferably six in number, and are arranged intermediate the lock lugs E and the outer thickened portion of the locking plate completely fills the space between the felly band B and the outer section 11 of the rim D and in this manner provides a positive support for the outer section, a support which is subjected only to compression strains. The tapered portion 14 provides for the easy applying of the rim on the wheel and the relatively slight circumferential extent of the locking plates offer very little frictional resistance to the removal of the rim. It is to be noted also that not only is a positive support provided, but the span both circumferential and lateral has been cut in half.

The impact lugs 17 preferably three in number, are secured to the outer section 10 of the rim D and are arranged at equal angular distances about the center of the wheel. These impact lugs are adapted to be impacted or struck by a hammer or like tool to induce movement of the section 10 with respect to the section 11, or in other words, to induce relative movement of the sections to thereby move the pins 12 with respect to the plate 13 to either cause the pins 12 to enter or leave the slots 16 of the plates 13 and so either to lock the section 10 to the section 11 or to release the section 10 from the section 11. These impact lugs are preferably secured to the section 11 by being spot-welded thereto.

The lock lugs E and the impact lugs 17 are so arranged with respect to each other, that three of the locks E are adapted to bear against the impact lugs 17, one against each impact lug and this provides a positive lock against movement of the outer section 10 with respect to the inner section 11 to release the sections from each other when the rim is in assembled position upon the wheel.

In practice, if it is desirable to remove the rim the lock lugs E are taken off and the rim and tire may be easily pulled from the felly. The tire is then laid flat, the operator stands

upon the casing F, if necessary, and the impact lug 17 is struck with a hammer or like tool to cause the outer section 10 to move in the direction indicated by the arrow in Fig. 3. This causes the lock pins 12 to leave the slots 16 of the locking plates 13, and when this occurs the sections 10 and 11 come apart easily and the tire is removed, repaired, and replaced, or a new tire is replaced if desired. The sections are then pressed together, with the locking pins adjacent the locking plates and the impact lug 17 is operated upon by the hammer to cause the sections 10 to rotate in the opposite direction and so have the locking pins 12 enter the slots 16, to assemble the rim, the inclined wall 16' of the slots drawing the sections tightly together. The rim is then placed upon the felly and the lock lugs replaced to lock the same thereon, and the rim together in assembled position. It is to be noted that the thickened portions of the locking plate by supporting the rim positively relieve the lock lugs of an excessive supporting strain which they are not well adapted to bear and which has frequently occasioned breakage of the lugs or bending of their supporting bolts, as well as distortion of the rim.

I claim:

1. A demountable rim including circumferential sections and interlocking means for said circumferential sections including locking pins on the outer of said sections and locking plates on the inner of said sections having slots to coöperate with said pins, said locking plates having supporting portions adapted to underlie said outer section to present a positive structure between the periphery of the wheel and the outer section to support said outer section and said locking plates having tapering portions adapted to exert a wedging action to facilitate the assembly of the rim on the wheel.

2. A demountable rim including circumferential sections and interlocking means for said circumferential sections including locking pins on the outer of said sections and locking plates on the inner of said sections having slots provided with inclined walls to coöperate with said pins to draw said sections together to form the rim, said locking plates having supporting portions adapted to underlie said outer sections to present a positive structure between the periphery of the wheel and the outer section to support said outer section and said locking plates having tapering portions adapted to exert a wedging action to facilitate the assembly of the rim on the wheel.

LOUIS HART KRICKEL.
